UNITED STATES PATENT OFFICE

OTIS H. HULLINGS, OF ALEXANDRIA, VIRGINIA

TRUCK

Original application filed March 14, 1928, Serial No. 261,468. Divided and this application filed January 29, 1929. Serial No. 335,979.

This invention appertains to improvements in trucks generally, and more particularly to a portable wheeled type of the same particularly adapted for use in conjunction with the laundry system forming the subject matter of my application for Letters Patent of the United States, Serial No. 261,468, filed March 14, 1928.

An object of the invention is to provide a truck of the class set forth, which is of a comparatively simple and inexpensive but durable and efficient construction and arrangement of parts, and which may be readily and easily moved from one place to another by being either pushed or pulled from either side or end thereof without need of any maneuvering the same into a particular direction of travel.

Another object of the invention is to provide a truck as hereinbefore characterized, which is provided with one or more article supports so mounted on the same in a manner that articles may be readily and easily placed in position thereon or removed therefrom by an attendant from either side or the ends of the truck as may be desired or necessary to lessen his or her labor, and to otherwise facilitate the loading and unloading operations.

A further object of the invention is to provide a truck of the character described, wherein the article supports aforesaid are preferably constituted in separate units of at least two shelves or trays each, one superposed above the other, and each unit is rotatably mounted so as to give the desired accessibility to the articles placed or nested in position on the shelves as hereinbefore indicated for the same.

Another object of the invention is to provide a hand truck of the type mentioned, which, in its particular adaptation for use as an adjunct to the laundrying operation, as set forth in my pending application aforesaid, allows for the assembling on the several shelves or trays of a number of individual wash receiving means, devices or containers, whereby the latter may be readily and easily transported from one laundry machine to another, each shelf or tray preferably having a capacity to receive the number of the means,

devices or containers required to completely fill, when in nested state, the cylinder or drum of a washing apparatus, and a drying machine or tumbler, and the rotor of a moisture extracting apparatus of a given size or capacity. 55

With the foregoing and other equally important objects and advantages in view, the invention resides in the certain new and useful combination, construction and arrangement of parts as will be hereinafter more fully described, set forth in the appended claims, and illustrated in the accompanying drawings, in which:

Figure 1 is a side elevation of a practical embodiment of the invention, 65

Figure 2 is a top plan view thereof, 66

Figure 3 is an end elevation of the same, 67

Figure 4 is a fragmentary vertical section through one of the article supporting units, and 70

Figure 5 is a slightly enlarged sectional detail through the lower end portion of one of the said supporting units. 75

Referring to the drawing, wherein like characters of reference designate corresponding parts throughout the several views thereof, the embodiment of the invention, as shown therein by way of example, is constituted in a tray-like base 10, which is mounted on suitable casters or wheels 11. Rising from the edge portions of the base 10 are spaced standards 12, which are connected at their upper ends by a continuous railing or the like 13. Extending transversely of the opposite longer sides of the railing 13 are spaced parallel intermediate members or bars 14, each of which act to strengthen the railing and, at the same time, to support centrally of the lower side thereof a suitable bearing 15 for the journaling therein of the upper end of a vertical shaft 16. The lower end of each shaft 16 is similarly journalled, in the bearing 17 secured in proper position on the upper side of the base 10. 85

Mounted concentrically on each shaft 16 in slightly spaced relation above the base 10 is a circular tray-like support 18, and above this support, equidistantly spaced from the same and the transverse bars 14, is a second support 19, of identical form, and on both of 100

which a group of the containers or baskets *a* are to be nested, after the manner of the similar nesting arrangement of the same in the several laundry machines as hereinbefore explained. These supports 18 and 19 are fixedly secured on the shafts 16 for revolving movements therewith. To lend greater stability to the trays or supports 18 and 19, under the weight of the loaded containers or baskets *a* nested thereon and when revolved with the shafts 16, suitable rollers or the like 20 are arranged in spaced circular series beneath the lower trays 18. These rollers 20, in each set of the same, preferably operate in an annular channel 21 secured in position on the upper side of the base 10, and are maintained in properly spaced relation in suitable mountings 22 secured at the under sides of the lower of the trays or supports 18, substantially as shown in Figure 5. A drain outlet 23 will be provided in the base 10 at a convenient point therein to allow for the discharge of accumulations of water therefrom, when the articles placed on the shelves or trays 18 and 19 contain moisture in a sufficient amount to overflow the flanged side edges of the latter.

Without further description, it is thought that the features and advantages of the invention will be readily apparent to those skilled in the art, and it will of course be understood that changes in the form, proportion and minor details of construction may be resorted to, without departing from the spirit of the invention or its scope as claimed.

Having thus fully described the invention, what is claimed is:

1. A truck comprising a flat wheeled base, a vertical shaft journalled at its lower end in said base, shelves fixedly mounted on said shaft in superposed relation, an open railing rising from the edges of said base and extending about the same, and a bearing carried at the upper side of said railing for the upper end of said shaft.

2. A truck comprising a flat wheeled base, a vertical shaft journalled at its lower end in said base, circular shelves fixedly mounted on said shaft in superposed relation, an open hand railing rising from the edges of said base and extending about the same, a transverse member at the upper side of said railing in which the upper end of said shaft is journalled, and roller supports beneath the lowermost of said shelves in equidistantly spaced relation about and adjacent to the outer edge thereof and bearing on said base.

3. A wheeled truck comprising a rectangular base of substantially tray-like form having a drain outlet leading from the same, a pair of rotatable shafts rising from said base in spaced relation on the longitudinal center thereof, a guard railing rising from and about the edges of said base, transverse members at the upper side of said railing in which

the upper ends of said shafts are journalled, and shelves fixedly mounted on each of said shafts in superposed relation.

4. A truck as set forth in claim 3 having roller supports beneath the lowermost of said shelves toward the outer edge thereof and bearing on said base.

5. A truck comprising a wheeled rectangular base, bearing members spaced on said base in the plane of the longitudinal center thereof, rotatable shafts rising from said bearings, a railing rising and about the edges of said base, transverse members in which the upper ends of said shafts are journalled, shelves fixedly mounted on each of said shafts in superposed relation, circular trackways arranged on said base in concentric relation about the said bearings thereon, and rollers arranged in spaced relation about the lower side of the lowermost of said shelves and engaged in said trackways.

6. A truck comprising a flat wheeled base, a vertical shaft journalled at its lower end in said base, circular tray-like shelves fixedly mounted on said shaft in superposed relation, an open hand railing rising from the edges of said base and extending about the same, a transverse member at the upper side of said railing, a bearing for the upper end of said shaft carried at the center of said transverse member, and roller supports beneath the lowermost of said shelves and arranged in equidistantly spaced relation about and adjacent to the outer edge thereof and bearing on said base.

In testimony whereof I affix my signature.
